US00D787995S

(12) **United States Design Patent** (10) Patent No.: **US D787,995 S**
(45) Date of Patent: **** May 30, 2017**

(54) **DISC BRAKE**

(71) Applicant: **GRIMECA S.R.L.**, Ceregano (IT)

(72) Inventors: **Massimo Betto**, Pernumia (IT);
Giuseppe Lisciani, Rovigo (IT)

(73) Assignee: **GRIMECA S.R.L.**, Ceregano (IT)

(**) Term: **15 Years**

(21) Appl. No.: **29/561,928**

(22) Filed: **Apr. 21, 2016**

(51) LOC (10) Cl. **12-16**

(52) U.S. Cl.

USPC **D12/180**

(58) **Field of Classification Search**

(57) **CLAIM**

The ornamental design for a disc brake, as shown and described.

DESCRIPTION

FIG. 1 is a perspective view of a disc brake, showing our new design;

FIG. 2 is a front elevation view thereof;

FIG. 3 is a left side elevation view thereof;

FIG. 4 is a rear elevation view thereof;

FIG. 5 is a right side elevation view thereof;

FIG. 6 is a top plan view thereof; and,

FIG. 7 is a bottom plan view thereof.

The dashed broken lines in the drawings show portions of the disc brake that form no part of the claimed design.

1 Claim, 7 Drawing Sheets
